PHONOGRAPH TURNTABLE DRIVE

Stuart J. Rodger, New York, N. Y., assignor to
Jacob Strauss and Isidore H. Goldman, both of
New York, N. Y.

Application December 24, 1937, Serial No. 181,495

4 Claims. (Cl. 74—190)

This invention relates to phonographs and more particularly to phonograph turntable drives. Still more particularly it relates to a phonograph turntable drive capable of operating at two different speeds.

In the art of sound recording and reproducing, and especially in the field of so-called "instantaneous" sound recording and reproducing, it is customary to employ two different speeds of rotation of the turntable carrying the record disk. Thus for records 12 inches or less in diameter a rotational speed of 78 R. P. M. is commonly employed. For records greater than 12 inches in diameter a speed of 33½ R. P. M. is used. It is customary in the art to use the same equipment for recording and reproducing sound at both of these speeds, in order to minimize overhead and investment and for convenience.

It is necessary that the turntable be capable of being rotated at exactly 33½ or 78 R. P. M. since these speeds have become standard in the art. It is highly desirable that the design of the equipment used be such that the change in rotational speed of the turntable from either of these speeds to the other be convenient and rapid. It is also desirable that it be effected without disassembly of any parts or without removal of the turntable. In addition, the drive for the turntable must be quiet and free from vibration which would affect adversely the quality of the recording or the reproduction. Moreover the design of the drive must be such that long-life of all moving parts is obtained.

Various expedients for obtaining the desired change in speed of the turntable have been heretofore suggested but so far as I am aware, none of them has been entirely successful. Many of them involve gearing and undue complication together with noisy and uncertain operation and short life. Many cause excessive vibration of the turntable with consequent detrimental effect upon the recording or reproduction. Others involve removal of the turntable in order to effect the change in speed. This is objectionable because of the length of time required, because of the inconvenience incurred and because of the resulting wear on the parts.

The principal object of this invention is to devise a phonograph turntable drive which overcomes the foregoing disadvantages and which attains many new advantages not heretofore attained in this art.

Another object of this invention is to devise a phonograph turntable drive with which vibration-free and uniform operation is attained; to-

gether with instantaneous changeability from either speed to the other.

Another object of this invention is to devise such a phonograph turntable drive which drives from one rim on the turntable rather than from two separate rims as disclosed in my copending application Serial No. 122,170, filed January 25, 1937, thereby saving considerable expense in machining and construction and avoiding the necessity for reversing the direction of rotation of the electric motor used as a source of power as the change in speed is effected.

Another object of this invention is to accomplish the foregoing objects while using friction idlers to transmit the driving power from the shaft of the electric motor used to the driving rim of the turntable. Use of friction drive and of idlers reduces vibration and variations in speed to a marked extent and is deemed necessary in order to obtain good recording and reproduction. My invention provides a turntable drive capable of driving the turntable at either of two desired speeds at will, while at the same time utilizing friction drive and friction idlers between the driving shaft and the driven rim of the turntable.

Referring to the accompanying drawing which portrays my invention in its preferred embodiment:

Figure 1 is a vertical sectional view along the line 1—1 of Figure 2.

Figure 2 is a horizontal plan view partly in section.

Figure 3 is a vertical sectional view along the line 3—3 of Figure 2.

The two speed turntable drive contemplated by this invention utilizes an electric motor the shaft of which projects vertically upward below the turntable. The turntable is provided with one downwardly extending driving rim which is most conveniently located at the outer edge of the turntable. The portion of the motor shaft which extends or projects above the lower edge of this driving rim is so constructed as to have two portions of different diameter, which are so calculated in relation to the diameter of the turntable driving rim that when this driving rim is driven from the smaller portion of the motor shaft it turns at a speed of 33½ R. P. M. and that when the driving rim is driven from the larger portion of the motor shaft, it turns at a speed of 78 R. P. M. In place of the specific speeds mentioned, speeds approximating thereto may be used. Thus in the device contemplated by this invention, I prefer to so calculate the sizes of the parts that speeds slightly in excess

of these standard speeds would theoretically obtain so as to compensate for the slight slippage encountered in practice.

The driving force of the motor is transmitted from the extending portion of the motor shaft described to the turntable driving rim by means of two rubber friction idlers disposed in a plane parallel to the turntable. These idlers are located between the motor shaft and the driving rim. One of these idlers is so disposed that upon moving the motor shaft in the proper direction the idler is driven by the smaller portion of the motor shaft and drives the turntable at the lower speed, namely $33\frac{1}{3}$ R. P. M., by contact with the driving rim. The other of these idlers is so disposed that upon moving the motor shaft in the opposite direction the idler is driven by the larger portion of the motor shaft and drives the turntable at the higher speed, namely 78 R. P. M., by contact with the driving rim.

The motor shaft is movable in a direction substantially perpendicular to a radius of the turntable. This movement is effected by mounting the motor on a movable lever which is pivoted to the panel under the turntable. The motor is capable of being placed in a neutral position in which it touches neither idler. It is also capable of being moved in either direction from this neutral position so as to cause the larger portion of its shaft to contact the idler for the higher speed or so as to cause the smaller portion of its shaft to contact the other idler for the lower speed.

The idlers used are preferably rubber rimmed metal wheels which construction gives high frictional driving power with very little vibration or fluctuation in speed. The idlers used are relatively large in diameter compared to the motor shaft (either the larger or the smaller section). This allows the motor shaft to make good frictional engagement with the idler. The idlers are relatively small compared to the size of the turntable driving rim. This allows very good contact with the turntable rim.

The idlers drive the turntable at either speed from the inside of the turntable rim. This allows a greater area of contact between the idler and the rim than if either of them were to drive against a rim which was convex as to it. Thus greater torque and a more even speed is made possible than in the construction where one idler drives a rim which is convex as to its, as in my copending application Serial No. 122,170 above identified.

Describing now the embodiment shown in the drawing: 1 represents a rotatable circular turntable the top portion of which is in the usual form, with a projecting pin 2 in its center to accommodate the record. Downwardly projecting shaft 3 of the turntable is of substantial diameter, say $\frac{1}{4}$ to 1 inch, and rests in the turntable bearing 4 which is of any suitable type and may comprise a closely fitting sleeve portion 5 and a steel ball 6 located in the rounded bottom portion 7 of the turntable bearing.

The turntable 1 is of metal such as cast aluminum and is formed or machined on its underside so that a driving rim 8 adapted to be driven by frictional engagement is formed. The diameter of this driving rim is variable within wide limits, and will depend largely upon the size of the turntable, it being usually most convenient to have it near the edge of the turntable 1 as shown in the drawing wherein the driving rim 8 is the inner circular edge of downwardly pro-

jecting solid edge portion 9. The driving rim 8 may be formed in any desired manner and may be machined in the turntable or may be formed separately and rigidly attached to the turntable by any suitable means.

Describing now the turntable drive itself, 10 represents a motor which is of any suitable type and is flexibly mounted on metal plate 11 by means of rubber mountings 12 and 13 which are of any ordinary type which permit the motor 10 to float and which absorb its vibration to a considerable extent. The plate 11 upon which the motor 10 is mounted is pivoted at one end by means of pivot 14 which allows the outer end 15 of plate 11 to move circumferentially in either 15 of the directions indicated by arrows 16 and 17. Motor mounting plate 11 is preferably located above the panel 18 which serves to cover the mechanism and as a support mounting the various parts as shown in the drawing. Thus 20 pivot 14 for the motor mounting plate 11 is preferably rigidly attached to the panel 18, as shown. At the outer end of motor mounting plate 11 is located an upwardly projecting threaded member 19 which projects through panel 18. At the end 25 of this threaded member 19 is a knurled knob 20 provided internally with threads which fit the cooperating threads of member 19. Thus when knob 20 is screwed down it locks plate 11 in the position in which it then is. When knob 20 is 30 loose it is used to push plate 11 backwards and forwards by means of member 19, thus causing the motor 10 to move backwards and forwards. Member 19 moves through a slot 21 the ends of which 22 and 23 act as stops to limit the 35 movement thereof and therefore the movement of plate 11 and of motor 10.

As the plate 11 is moved in either direction away from the middle neutral position, it carries the motor 10 and consequently the motor shaft 40 indicated generally as 24 with it in the same direction. The motor shaft 24 is therefore moved in a direction substantially perpendicular to a radius of the turntable. In the neutral position of the parts in which position the parts 45 are shown in the drawing, the motor shaft 24 is in a neutral position in the middle of the path of its travel.

Motor shaft 24 projects upwardly beneath the turntable 1 as shown. The portion of the motor 50 shaft 24 which projects upwardly beyond the lower edge of the driving rim 8 of the turntable is machined or otherwise constructed so as to form a larger portion 25 and a smaller portion 26. This construction may be attained by 55 tightly fitting sleeves which are tightly fitted onto the motor shaft 24, as indicated in the drawing, or it may be attained by machining down the projecting portion of motor shaft 24, where this shaft is of sufficient size to enable this to be done. As the motor shaft 24 is moved in the direction corresponding to movement of plate 11 in the direction of arrow 17, it drives the turntable at the higher speed (78 R. P. M.) by means 60 of rubber friction idler 27 which the larger portion 25 of the motor shaft 24 frictionally engages. Idler 27 then drives the turntable by frictional engagement with the turntable driving rim 8.

As the motor shaft 24 is moved in the direction corresponding to movement of plate 11 in the direction of arrow 16, it drives the turntable 1 at the lower speed ($33\frac{1}{3}$ R. P. M.) by means of rubber friction idler 28 which frictionally engages 75

the smaller portion 26 of the motor shaft. Idler 28 then drives the turntable 1 by frictional engagement with the turntable driving rim 8.

The parts, namely, idlers 27 and 28, motor shaft 24 together with its larger and smaller portions, 5 25 and 26, respectively, are so arranged that when the motor is in the driving position for either idler, the point where the driving portion 10 25 or 26 of the motor shaft 24 contacts the rubber idler 27 or 28, the point where the idler 27 or 28 contacts the turntable driving rim 8 and the point 15 where the axis of the idler support intersects the circle representing the periphery of the idler 27 or 28 are all substantially 120° apart. This construction is not vital to the operation of the 20 device but results in the most efficient transmission of the driving force from the motor shaft 24 to the turntable rim 8 at either of the two speeds.

Idlers 27 and 28 are not located in the same horizontal plane. Idler 28 which contacts the upper and smaller driving portion 26 of the motor shaft is located in a plane above the plane of idler 27 which contacts the lower and larger driving portion of the motor shaft.

The idlers 27 and 28 are metal wheels having relatively thick rubber rims 29 and 30 respectively, although they may be of any other construction provided they are adapted to frictionally transmit the torque of the motor to the turntable in a satisfactory manner and are of such materials as to have desirable long wearing qualities. The use of these friction idlers is highly desirable since they act as filters, absorbing whatever 35 minute vibrations are set up by the motor before they reach the turntable. Idlers 27 and 28 are driven by straight line engagement with the driving portions of motor shaft 24 and drive the turntable 1 by straight line engagement with the driving rim 8 of the turntable 1.

The idlers 27 and 28 are mounted so as to rotate about bearings 31 and 32 at their center. Bearings 31 and 32 are preferably self-oiling bearings which prevents oil getting on the idler friction surfaces and ruining them; by disintegrating the rubber or by destroying the frictional engagement between the idler surface and the rim or the motor shaft.

Idlers 27 and 28 are supported in such a manner that they may move outwardly so as to engage the driving rim 8. This is accomplished by means of flat supporting members 33 and 34, respectively, which are pivoted so as to be movable about fixed pivots 35 and 36, respectively. Idler 28 is so mounted as to rotate about pin 38 by means of its own bearing surface 32 and pin 38 is integrally fastened to supporting member 34. Idler 27 is so mounted as to rotate about pin 37 by means of its own bearing surface 31 and pin 37 is integrally fastened to supporting member 33.

Idler supporting members 33 and 34 are movable about fixed pivots 35 and 36, respectively, which are preferably integrally attached to main panel 18, as shown. The construction shown enables the idlers to float freely and to absorb vibration to the fullest extent.

The mode of operation of the device will be obvious from the foregoing description. However, it may be described in detail as follows:

The motor 10 is in its neutral position as shown in the drawing. It is started by sending an electric current through it. After it has come up to speed it is moved in a direction corresponding to movement of plate 11 in the direction of arrow 17.

This movement is accomplished by moving plate

11 by means of knob 20 whereupon knob 20 is tightened to lock the plate 11 and the motor in position. As the motor is moved in this direction the larger portion 25 of the projecting portion of the motor shaft 24 contacts idler 27 which begins 5 to rotate. As the motor is continued in its movement until pin 19 touches stop 23, idler 27 which is now rotating contacts the rim 8 of the turntable causing it to rotate at the higher speed (78 10 R. P. M.) in the direction indicated by the arrow 19 in Fig. 2. When it is desired to cause the turntable at the other and lower speed the motor is moved in the other direction until pin 19 touches stop 22 and the motor drives the turntable through the smaller portion 26 of the projecting 15 motor shaft and idler 28.

When the apparatus is not in use, the speed control knob 20 is moved to the center position, freeing the idlers from the turntable rim 8 and the driving portions of the motor shaft, relieving 20 the pressure and lengthening their life.

As will be obvious the projecting portion of the motor shaft 24 is machined to the proper sizes so that the desired speeds are obtained. These sizes are calculated with reference to the diameter of 25 the driving rim 8 and with reference to the speed of rotation of the motor shaft 24. Thus when using a motor having a speed of 1750 R. P. M., and a driving rim having a diameter of 16 inches, the smaller part 26 of the motor shaft is made 0.310 30 inch in diameter and the larger part 25 is made 0.730 inch in diameter. These sizes cause the turntable to rotate at speeds of 33.6 R. P. M. and 80 R. P. M., respectively. These increases over standard speeds of 78 R. P. M. and 33 1/3 R. P. M. 35 have been found sufficient to allow for the slight loss in speed due to slippage.

The advantages of this drive are numerous. One advantage is that change in speed is secured instantly by moving a lever, it being unnecessary to remove the turntable or any idlers to effect the change in speed. Another advantage is that by having a neutral position in which the idlers are not under pressure, the life 40 of the idlers is increased considerably. Also because it is not necessary to remove the idlers to change the speeds, an automatic self-oiling bearing can be used on them. This prevents oil getting on the idlers and ruining them. By having suitable stops to limit the motor movement, 45 the correct pressure on the idlers is assured. The turntable is readily removable from the machine by simply pulling it upward, which gives free access to any of the working parts. Since the turntable is driven at both speeds on its outer 50 rim a greater torque is developed at both speeds than is the case where the turntable is driven at one speed by a driving rim which is small in diameter as in my copending application Serial No. 122,170, above identified. In the device contemplated by this invention the turntable is 55 driven at either speed by means of an idler which contacts a driving rim which is concave relative to it. This gives better frictional transmission to the turntable driving rim than is the case in 60 my application Serial No. 122,170 wherein the drive at the higher speed is by means of a driving rim which is convex relative to the surface of the driving idler. Another advantage of this invention is that the device contemplated thereby 65 makes it unnecessary to reverse the direction of the motor as it is moved from driving engagement at one speed to driving engagement at the other speed. The elimination of this reversing switch makes for simplicity of construction and 70

75 75

operation and lessens the cost of construction. Also it makes possible a more rapid change of speed as it is not necessary to let the motor come to a stop before changing to the other speed.

5. While generally it will be desirable to operate the machine with the turntable in the horizontal plane, as shown in the drawing, it will be appreciated that if desirable it may be operated with the turntable in a vertical plane. The principle 10 of my invention is applicable regardless of the plane in which the turntable is located.

Having described my invention, what I claim is:

1. A two-speed phonograph turntable drive 15 capable of operating at either a lower or a higher speed comprising, in combination, a rotatable circular turntable having a downwardly extending circular driving rim, an electric motor so located that its shaft projects upwardly above the lower edge of said driving rim, the projecting portion of said motor shaft having a smaller and a larger circular driving portion, a lower speed friction idler located between the smaller portion of said motor shaft and said driving rim, a higher speed friction idler located between the larger portion of said motor shaft and said driving rim, said motor shaft being movable in a plane parallel to the turntable in such manner that its smaller portion may drive the turntable 20 at the lower speed through said lower speed idler and said driving rim and that its larger portion may drive the turntable at the higher speed through said higher speed idler and said driving rim.
2. A two-speed phonograph turntable drive 25 capable of operating at either a lower or a higher speed comprising, in combination, a rotatable circular turntable having a downwardly extending circular driving rim, an electric motor so located that its shaft projects upwardly above the lower edge of said driving rim, the projecting portion of said motor shaft having a smaller and a larger circular driving portion, a lower speed friction idler located between the smaller portion of said motor shaft and said driving rim, a higher speed friction idler located between the larger portion of said motor shaft and said driving rim, said idlers being mounted on movable supporting members so that they are free to move outwardly to contact said driving rim, 30 said motor shaft being movable in either direction along a line substantially perpendicular to a radius of the turntable and being so located that as it is moved in one direction its smaller portion drives the turntable at the lower speed 35 through said lower speed idler and said driving rim and as it is moved in the other direction its larger portion drives the turntable through said higher speed idler and said driving rim, the arrangement of the parts being such that when 40 the motor shaft is in the driving position for either idler the point where the driving portion of the motor shaft contacts the idler, the point where the idler contacts the driving rim and the point where the axis of the idler supporting 45 member intersects the periphery of the idler are all substantially 120° apart.
3. A two-speed phonograph turntable drive 50

5. capable of operating at either a lower or a higher speed comprising, in combination, a rotatable circular turntable having a downwardly extending circular driving rim, an electric motor so located that its shaft projects upwardly above the lower edge of said driving rim, the projecting portion of said motor shaft having a smaller and a larger circular driving portion, a lower speed friction idler located between the smaller portion of said motor shaft and said driving rim, a higher speed friction idler located between the larger portion of said motor shaft and said driving rim, said idlers being so supported that they are free to move outwardly to contact said driving rim, said motor shaft being movable in either direction along a line substantially perpendicular to a radius of the turntable and being so located that as it is moved in one direction, its smaller portion drives the turntable at the lower speed through said lower speed idler 20 and said driving rim and that as it is moved in the other direction its larger portion drives the turntable at the higher speed through said higher speed idler and said driving rim.

4. A two-speed phonograph turntable drive 25 capable of operating at either a lower or a higher speed, comprising in combination, a rotatable circular turntable having a downwardly extending circular driving rim, an electric motor so located that its shaft projects upwardly above the lower edge of said driving rim, the projecting portion of said motor shaft having a smaller and a larger circular driving portion, a lower speed friction idler located between the smaller portion of said motor shaft and said driving rim, a higher speed friction idler located between the larger portion of said motor shaft and said driving rim, said idlers being mounted on movable supporting members so that they are free to move outwardly to contact said driving rim, 30 said motor shaft being movable in either direction along a line substantially perpendicular to a radius of the turntable and being so located that as it is moved in one direction its smaller portion drives the turntable at the lower speed 35 through said lower speed idler and said driving rim and as it is moved in the other direction its larger portion drives the turntable through said higher speed idler and said driving rim, the arrangement of the parts being such that when 40 the motor shaft is in the driving position for either idler the point where the driving portion of the motor shaft contacts the idler, the point where the idler contacts the driving rim and the point where the axis of the idler supporting 45 member intersects the periphery of the idler are all substantially 120° apart.

STUART J. RODGER.
